US00D927111S

(12) **United States Design Patent** (10) Patent No.: **US D927,111 S**
(45) Date of Patent: ** Aug. 3, 2021

(54) **WASHING MACHINE**

- (71) Applicant: **Samsung Electronics Co., Ltd.**, Suwon-si (KR)
- (72) Inventors: **Sanghoon Yoon**, Suwon-si (KR); **Myunggyu Kim**, Suwon-si (KR); **Jaejin Lee**, Suwon-si (KR)
- (73) Assignee: **SAMSUNG ELECTRONICS CO., LTD.**, Gyeonggi-Do (KR)

(**) Term: **15 Years**

(21) Appl. No.: **29/684,209**

(22) Filed: **Mar. 19, 2019**

(30) **Foreign Application Priority Data**

- Nov. 19, 2018 (KR) 30-2018-0053586
- (51) LOC (13) Cl. **15-05**
- (52) U.S. Cl. ..... USPC **D32/28**

(57) **CLAIM**

The ornamental design for a washing machine, as shown and described.

DESCRIPTION

FIG. 1 is a front perspective view of a washing machine, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion 8 in FIG. 1;

FIG. 9 is an enlarged view of the encircled portion 9 in FIG. 2;

FIG. 10 is an enlarged view of the encircled portion 10 in FIG. 4; and,

FIG. 11 is an enlarged view of the encircled portion 11 in FIG. 5.

The even-dash broken lines illustrating portions of the washing machine form no part of the claimed design. The dot-dash broken lines illustrate the boundary of the claimed design and form no part of the claimed design. The dot-dot-dash broken lines encircling enlargement portions of the Washing Machine form no part of the claimed design.

1 Claim, 11 Drawing Sheets
